UNITED STATES PATENT OFFICE.

JOSEF KORBULY, OF ARAD, AUSTRIA-HUNGARY.

AXLE-BEARING.

SPECIFICATION forming part of Letters Patent No. 631,400, dated August 22, 1899.

Application filed September 21, 1897. Serial No. 662,500. (No model.)

To all whom it may concern:

Be it known that I, JOSEF KORBULY, a subject of the Emperor of Austria-Hungary, residing at Arad, Austria-Hungary, have invented certain Improvements in the Bearings for Axles of Railway-Cars and the Like; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention is an improvement on the subject-matter of my previous Letters Patent, No. 558,693, dated April 21, 1896, and has for its object increased facility in the lubrication of the journal and bearings, as well as greater simplicity and compactness.

In the accompanying drawings, Figure 1 represents a longitudinal vertical section of a journal-box and inclosed parts embodying my invention, the journal being shown in side elevation. Fig. 2 represents a central transverse section of the same. Fig. 3 represents a transverse section of the same, taken on a plane at the inner edge of the washers and looking outward. Fig. 4 represents a detail sectional view of the under part of the washer and devices for holding it in place. Fig. 5 represents a view, similar to Fig. 1, of a slightly-modified form of my device. Fig. 6 represents a view of the same similar to Fig. 3. Fig. 7 represents a detail view, similar to Fig. 4, of the modified form of washer and clamping devices illustrated in Figs. 5 and 6. Fig. 8 represents a view, similar to Figs. 1 and 5, of another modification. Fig. 9 represents a detail view, partly in elevation and partly in section, of the washer, tightening-nut, and proximate devices. Fig. 10 represents a detail view of the said tightening-nut, its screw, and the frame or case in which it works, the parts having the construction shown in Fig. 1. Fig. 11 represents a view, similar to Figs. 1, 5, and 8, of another modification. Fig. 12 represents a transverse central section of Fig. 11. Fig. 13 represents a side elevation of another modification with interior parts indicated by dotted lines; and

Fig. 14 represents a vertical section through Fig. 13, taken at the rear end of the brasses.

In practical use of my devices shown in Patent No. 558,693 I have found that the journal-bearings wear very little, so that there is no great need to make them rotatable. Also I have found that the rapid rotation of the axle-journal in the bearing-brasses forms a partial vacuum in the narrow interval between them, so that the oil is sucked up from below to the journal if any passage be left for it. To utilize this latter fact and in view of what is above stated with regard to the bearings, as well as for the purpose of permitting the boxes of car-axle journals to be manufactured more cheaply and simply than heretofore, I have invented the following construction.

A designates the journal-box, inclosing the journal C of the car-axle and the bearing-brasses d d', the said box resting on the upper brass d, to which the upper part of the said box is fastened by screw t in the forms of my invention illustrated by Figs. 1, 2, and 5. The body A' of this box is cylindrical and fits the said brasses closely. An oil-reservoir B below the said body and also extending up outside the end of the journal is provided with a thin outer shell D, which is integral with the said body and forms a part of the said box. This shell is curved transversely, as shown in Fig. 2, and also longitudinally, as shown in Figs. 1, 5, and 8, giving it a peculiar shape corresponding to a longitudinal semi-cylindrical section of a pipe running along the under side of the said box-body and bent up to cover its outer end, which would otherwise be open. The lower brass or bearing d' is provided with a central funnel-like aperture l³, which communicates with the upper end of the central bore l' of a tube l, the latter being cast with the box-body A' and extending downward therefrom into the said oil-reservoir. The oil is fed to the said reservoir through holes in the top of the said box, near the ends thereof, one of which (marked m²) is shown in Fig. 8. One of these is normally closed by a plug m and the other by a screw m'. The suction due to slight irregularities in the running of the journal draws up the oil to the said journal through the pas-

sage provided by aperture l^3 and bore l^2 . An annular washer s , of felt or other soft material, fits on the inner flange p of the journal C . This washer is of sickle form in cross-section, as shown in Fig. 4. Its flat horizontal part is of course in contact with the said journal at the bottom or lowest longitudinal line of the latter, (indicated by a line drawn on Fig. 4,) while its vertical part is clamped below the said journal, between the inner end of the said box and a fastening-plate r , by means of a bolt r' , that passes through the said plate into the said box. I also employ a tightening-ring o , surrounding the flat horizontal part of the said washer, as shown in section in Figs. 1 and 4, and tightened by a nut g and screw f , the latter working through a fixed part of a casing or frame e , which is integral with the said axle-box. These tightening devices are most distinctly shown in Figs. 10 and 11. The washer thus held in place and tightened prevents the oil from passing out of the inner end of the journal-box and along the axle or on the ground below.

In journal-boxes fitting close to the outer face of the wheel E , as shown in Fig. 5, I substitute for the said ring r a grooved collar y , which is screwed to the inner end of the axle-box and allows the latter to be made shorter, a leak-preventing washer s' (see also Fig. 6) being held in place by the said collar.

As shown in Fig. 8, the box-body A' sometimes also serves for a bearing, the ordinary brasses being dispensed with. In this case the central bore of tube l extends to the journal and has a funnel-shaped top. On account of this difference in construction I have marked the said bore l' in the said figure.

In journal-boxes having an upper brass D' , Figs. 11, 12, 13, and 14, but no lower brass, I attach to the upper brass a lower semicylindrical bearing D'' , which is fastened to the said upper brass by lugs k' and bolts k , Figs.

11 and 12, or by outer encircling rings $z z'$, Figs. 13 and 14. This lower bearing D'' is provided with the downwardly-extending tube l and its bore l' of Fig. 8. As shown in Fig. 11, the journal-box used with this modification of my invention does not correspond to the journal or bearing, but is flat at the bottom. It has no auxiliary shell D , but is closed at the end and adapted to hold oil, so that the operation is the same as hereinbefore described.

Having thus described my invention, what I claim as new, and desire to secure by Letters Patent, is—

1. A journal-box provided with a reservoir for oil extending below the said box, a perforated bearing for the journal, and a tube extending downward into the oil and affording a passage for the same up through the aperture of the bearing to the journal substantially as set forth.

2. An axle-box provided with a cylindrical body A' and a shell forming an oil-reservoir below the latter, in combination with a brass d' within the said body and a tube extending down from said body into the oil, the bore of the said tube and a registering aperture in the said brass affording a continuous oil-passage to the journal, substantially as set forth.

3. In combination with an axle-journal and its box, an oil-retaining annular washer fitting on the said journal and provided with a vertical part, and a retaining-plate and bolts whereby the said vertical part is clamped to the inner end of the said box, substantially as set forth.

In witness whereof I have hereunto set my hand this 31st day of July, 1897.

JOSEF KORBULY.
